CARRY BAG HANDLE CONSTRUCTION

Albert Soffa, Philadelphia, Pa., assignor to Wolf Brothers, Inc., Philadelphia, Pa., a corporation of Pennsylvania

Application March 7, 1950, Serial No. 148,051

2 Claims. (Cl. 229—54)

1

This invention relates to an improvement in paper bags and more particularly to an improvement in the handle construction of paper bags of the type generally known as a carry bag.

This invention comprises an improvement in the handle structure of the type of bag shown in the Patents No. 2,172,555 and No. 2,364,836 issued to Howard A. Wolf.

It is an object of the present invention to provide a handle structure which will increase the strength of the strip on the bag back between the handle cut-out and the open end of the bag before the carrying handle structure is formed into position for carrying the bag.

It is a further object of this invention to provide an edge adjacent to the top of the handle aperture which has a flat surface after the handle structure has been formed into position for carrying the bag and is more comfortable to the feel of one carrying the bag.

It is a further object of the present invention to provide a reenforcing flap across the top of the handle aperture which is automatically folded into proper position when the handle structure is formed into carrying position.

It is a further object of this invention to provide reenforcing for the strip between the handle aperture and the open end of the bag increasing the strength of the strip before the bag handle structure is formed into carrying position, which will provide reenforcing of the bag handle after the bag handle is formed into carrying position and which will not complicate the mode of forming the handle into carrying position or in any way prevent the operation of forming the handle into carrying position from being completely self-suggestive with no special instructions to the user being necessary.

These and other objects of the invention will become apparent from the following description when read in conjunction with the accompanying drawings, in which:

Figure 1 is a partially cut-away back view of one form of a carry bag constructed in accordance with the present invention showing the bag closing flap in open position;

Figure 2 is a partially cut-away enlarged back view of a bag of the form shown in Figure 1 showing the handle area with the handle structure partially formed into carrying position;

Figure 3 is a partially cut-away enlarged front view of a bag of the form shown in Figure 1 showing the handle area with the handle structure completely formed into carrying position;

Figure 4 is a view showing a section through

2

the handle structure taken on the plane indicated by the trace 4—4 in Figure 3;

Figure 5 is an enlarged back view showing the handle area of a bag embodying an alternate form of the present invention and showing the bag closing flap in an open position;

Figure 6 is a partially cut-away enlarged front view showing the handle area of a bag of the type shown in Figure 5 and showing the handle formed into carrying position;

Figure 7 is an enlarged back view showing the handle area of a bag embodying another alternate form of the present invention and showing the bag closing flap in an open position; and

Figure 8 is a partially cut-away front view showing the form of the invention shown in Figure 7 and showing the handle structure formed into carrying position.

In Figure 1 there is shown a bag comprising a rear wall 1, a front wall 2, side flaps 3 and a closing flap 4. The side flaps 3 are extensions of the front wall 2 which are turned inwardly and are secured with adhesive or other suitable means to the inside of the back wall 1 of the bag.

In this figure the front and back walls of the bag are shown as one continuous piece of material folded across the bottom of the bag to form the front wall 2 and the back wall 1 using the side seam construction. It will be obvious, however, that the present invention may be incorporated in bags having a single seam disposed at the rear of the bag, and a transverse seam along the bottom of the bag or other suitable form of construction wherein a suitable closing flap is provided to be folded down over the open end of the bag as will be hereinafter described.

Attached to the inside of the back wall 1 of the bag by adhesive or other suitable means is the reenforcing patch 5 and attached to the inside of the closing flap 4 and extending downwardly and attached to the inside of the front wall 2 by adhesive or other suitable means is the reenforcing patch 6 which lies in a position on the front wall 2 superimposed underneath the reenforcing patch 5 on the back wall 1. The top of the back wall 1 adjacent to the bag opening is cut with inclined form providing a peak 9 of maximum height in the center of the back of the bag for cooperation with the handle flap as will be hereinafter described.

The handle structure of the carry bag includes the finger cut-outs 7 which are cut through the rear and front walls 1 and 2 of the bag and their reenforcing patches 5 and 6, and a locking tongue 8 which is formed in the closing flap 4

55

by the cut lines 10 and is adapted to be folded downwardly and passed through the cut-outs 7, as will be hereinafter described. The cut lines 10 provide at either end of the locking tongue the ears 11. The upper edge of the handle cut-out 7 in the back bag wall 1 is provided with a flap 12 and the upper edge of the handle cut-out in the front bag wall is provided with the flap 13. The cut-outs 7 and the flaps 12 and 13 lie in superimposed position as viewed in Figure 1.

The bag may be formed of paper or other material suitable for the formation of a carry bag and the reenforcing patches 5 and 6 may be made of paper or other suitable reenforcing material being somewhat more stiff than the material forming the bag itself.

Heavy score lines 16 and 17 are provided at the root of the tongue between the cuts 19. Heavy score lines 19 and 20 are provided in the area where the flap 4 joins the front wall 2 of the bag across the width of the reenforcing patch 6. Heavy score lines 21, 22 and 23 are provided along the length of the flap 13 and heavy score line 24 is provided along the length of the flap 12. A light score line 25 is provided across the width of the bag between the heavy score lines 19 and 20, and a plurality of light score lines 26 are provided between the heavy score line 17 at the root of the tongue and the heavy score line 19 across the width of the patch 6.

In use the bag will generally be opened by the user grasping the central portion of the closing flap 4 in the region of the reenforcing patch 6 and the strip of material 28 in the back of the bag lying between the back cut-out 7 and the upper edge of the back of the bag. The user will draw these two portions of the bag apart thereby opening the bag to permit insertion of an article therein. In performing this operation the user will, in passing his fingers through the cut-out opening 7, bend the flap 12 at an angle to the strip 28 thereby providing a stiffener or reenforcement which serves to strengthen the strip 28 and reduce the possibility of tearing or deforming the strip 28 while the bag is being filled. It has further been found that the yielding action of the strip has the psychological effect of warning the user of the relative weakness of the strip 28 when held in this position. Thus, the flap 12 serves in various ways to accomplish what amounts to, in effect, greatly increasing the strength of the strip 28.

After articles have been placed in the bag, the user will, without any instructions being necessary, immediately determine by viewing the bag that to form the handle of the bag the flap 4 must be folded down over the back 1 of the bag into position, as shown in Figure 2. The light score line 25 across the width of the bag and the heavy score lines 19 and 20 across the width of the reenforcing patch 6 will facilitate this folding. It should be noted that the major amount of bending will take place on the two heavy score lines 19 and 20 and a lesser amount of bending will take place on the light score line 25, and the peaked center 9 of the bag back will butt against the bend on the light score line 25. Thus there is provided a substantially flat top portion for the bag which will tend to stiffen the handle structure, as will be hereinafter described more fully and at the same time sharp bends which might tend to crack or break the bag material are avoided.

The next step in forming the handle structure is to press the tongue portion 8 through the

aligned cut-outs 7 and fold the tongue upwardly against the front wall of the bag providing the completely formed handle, as shown in Figures 3 and 4. When the handle has been formed into this carrying position, the flaps 12 and 13 will be bent over as shown in Figure 4 on their respective heavy score lines 21 and 24. The flap 12 being the inner flap, it is necessary that it be bent about a sharper radius than the flap 13. This bending is facilitated by the additional heavy score lines 22 and 23. Score lines 22 and 23 also reduce the sharpness of the bend occurring on the score line 21 and thus reduce the tendency of cracking therealong. Score lines 16 and 17 at the root of the tongue form between them the reenforcing strip 18 which is arranged to be at least as wide as the folded flaps 12 and 13 which, after the handle is formed, as shown in Figures 3 and 4, are disposed between the tongue which now lies on the front of the bag and the closing flap which now lies on the back of the bag.

It will be observed from viewing Figures 3 and 4 that the ears 11 of the tongue 8 spring downwardly toward the bottom of the bag after the tongue is passed through the cut-outs 7 and formed upwardly into carrying position thus serving to lock the tongue in its folded position. The flaps 12 and 13 serve as expandable members exerting a force against the tongue 8 and tend to hold the strip 18 in position, and the tongue 8 is kept from turning downwardly and passing back through the cut-outs 7 as a result of this force by the locking action of the ears 11 which bear against the front wall of the bag.

The score lines 26 across the width of the front reenforcing patch between the tongue and the score line 19 create in the closing flap 4 a slightly rounded contour, as shown in Figure 4, when the bag handle structure is formed into carrying position.

When the bag structure is formed in the manner indicated the resulting carrying handle structure, as shown in Figures 3 and 4, provides a handle structure having the following features of note. At the top of the cut-outs 7, the portion of the handle engaging the user's hand presents to the user a flat surface 18 which has, because of its flat formation, sufficient resistance to maintain the top of the bag in a flat position while being carried. It will be noted that the surface 18 is in substantially flat engagement with the flap 12, along its entire length and that the flap 12 is in engagement with the flap 13 along its entire length. This stiffness is further enhanced by the substantially flat portion of the front reenforcing flap lying across the top of the bag between the score lines 19 and 20. These various substantially flat surfaces lying on planes generally perpendicular to the bag panels all impart stiffness to the handle area and tend to resist transverse bending of the upper part of the bag.

Further contributing to the user's comfort is the fact that the handle has a rounded feeling as a result of the effect of the tongue on the front 65 of the bag when it is bent up from the cut-outs and the rounded contour on the back of the handle as produced by the score lines 26, as has been hereinbefore described in connection with Figure 4.

An alternate form of this invention is shown in Figures 5 and 6 wherein a bag has a back wall 40, a front wall 42, a closing flap 44, a reenforcing patch 46 attached to the inside of the back wall and a reenforcing patch 48 attached to the inside of the closing flap and the front wall. The

bag is provided with cut-outs 49 and a tongue 50 defined by cut lines 51.

In this form of the invention there is provided adjacent to the top edge of the cut-outs 49 the flaps 52 and 53 defined by the score lines 45 and 47 on the front and back bag walls, respectively. The flaps 52 and 53 are of substantially diamond or oval shape and there is similarly provided in the bag closing flap 44 in the area between the tongue 50 and the portion adjacent to the top of the bag, the portion 54 defined by the score lines 43 and which is substantially diamond or oval shape and is formed generally identical in shape to the formation of the flaps 52 and 53. The flap 52 is provided with the additional score line 55. When the bag flap 44, which is in an open position, as shown in Figure 5, is folded down over the back of the bag and the tongue 50 is pressed through the cut-out 49 and bent upwardly on the front of the bag forming the handle structure, as shown in Figure 6, the portion 54 will lie flat against the user's hand and the flaps 52 and 53 will lie above and generally in alignment with and flat against the portion 54. The portion of the re-enforcing patch 48 forming the top of the bag is provided with heavy score lines 56 and 58 and the light score line 61. The re-enforcing patch 48 is also provided with light score lines 62 similar to those provided in the embodiment shown in Figure 1.

When the handle of the form shown in Figures 5 and 6 has been formed in position, a section therethrough will have substantially the same appearance as that shown in Figure 4. The primary advantage of this form of the invention is that a crowned or arched surface as indicated at 64 is presented to the user's fingers providing greater comfort and greater stiffness when the bag is held.

Still another modification of the invention is shown in Figures 7 and 8 wherein the front portion of the bag above the cut-out 70 is provided with the pair of oval or diamond-shaped flaps 71 and the back portion of the bag above the cut-out 70 is provided with a pair of similarly formed flaps 72. The bag closing flap area lying between the tongue 74 and the portion of the bag flap 75 between the tongue and the top of the bag is provided with score lines forming the areas 76 and 77 which, when the handle is formed into position, are adapted to fall into alignment with the areas 70 and 71. It will be noted that the flaps 72 being the inside flaps when formed are provided with the additional score lines 73, and the portion of the tongue root between the areas 76 and 77 is provided with the additional score lines 78 and 79. The score line 73 reduces the sharpness of the bend along the flap 72 and the score lines 78 and 79 are desirably included to reduce the sharpness of the bend along the score line 80. These score lines are desirable inasmuch as too sharp a bend along the score lines on the re-enforcing patch create a susceptibility to cracking. Hence, the score lines 78 and 79 accommodate some of the bending and tend to relieve the degree of bending existing along the line 80 when the handle is formed into form for carrying, as shown in Figure 8.

In this form of the invention the flaps 71 and 72 above the cut-outs lie substantially flat against the flat surfaces 76 and 77, respectively, at the root of the tongue. This is essentially the same structure as produced by the preceding

forms except that two arches are formed as shown generally at 81 and 82 in Figure 8.

It will be observed that the modification shown in Figures 5 and 6 and the modification shown in Figures 7 and 8 relate essentially to the shaping of the stiffening flaps across the top of the handle cut-out, and are illustrative of the fact that a great variety of shapes of stiffening flaps may be provided without departing from the invention disclosed herein.

It will be apparent that a variety of modifications may be made in the embodiment of the invention as disclosed herein without departing from the scope of the invention claimed. Either the front or the back bag panel may be extended to form the bag closing flap. While reenforcing pads have been shown in the handle region as providing the most desirable bag structure, it will be apparent that if the entire bag is made from material having sufficient stiffness, these reenforcing pads may be omitted. In the event that the reenforcing pads are omitted the score lines which now extend for the width of the re-enforcing pads will preferably be extended across the greater portion of, or the total width of, the bag.

It will be apparent that various modifications may be made in the form and location of the cut-outs which provide for the insertion of the user's fingers.

Various modifications may also be made in the arrangement of the flaps employed. There is disclosed herein the arrangement having flaps extending into the cut-outs from both bag panels, however, a satisfactory structure also results if a flap or flaps are extended from one panel only and arranged to bend and engage the cut edge forming the top edge of the cut-out in the other panel. These and other modifications may be made to the structure disclosed herein without departing from the scope of the invention as set forth in the following claims.

What is claimed is:

1. A carry bag comprising front and back panels separated at their upper ends to form an opening for the bag, finger openings in said front and back panels, a closure member extending upwardly from one of said panels and adapted to be folded down over the other of said panels closing said bag opening, a flap member extending downwardly from the other of said panels into the finger opening therein a distance substantially less than half the height of the finger opening and joined to the upper edge of the opening along a weakened bend line, and a tongue member formed integral with said closure member, hinged thereto along a weakened bend line and adapted to be folded through said finger openings after said closure member is folded down, said tongue member having an additional bend line extending parallel to its above mentioned bend line and spaced therefrom a distance approximately equal to the distance between the free edge of said flap member and its bend line, said flap member being adapted to bend on its bend line and lie with a substantial portion of the flap member substantially in surface contact with the portion of the tongue between the two tongue bend lines and in a plane substantially perpendicular to its associated bag panel when said tongue is folded through said finger openings.

2. A carry bag comprising front and back panels separated at their upper ends to form an opening for the bag, finger openings in said front and back panels, a closure member extending up-

wardly from one of said panels and joined thereto along a weakened bend line and adapted to be folded down along said bend line and over the other of said panels closing said bag opening, a flap member extending downwardly from the other of said panels into the finger opening therein a distance substantially less than half the height of the finger opening and joined to the upper edge of the opening along a weakened bend line, and a tongue member formed integral with said closure member, hinged thereto along a weakened bend line and adapted to be folded through said finger openings after said closure member is folded down, said tongue member having an additional bend line extending parallel to its above mentioned bend line and spaced therefrom a distance approximately equal to the distance between the free edge of said flap member and its bend line, said flap member being adapted to bend on its bend line and lie with a substantial portion of the flap member substantially in surface contact with the portion of the tongue between the two tongue bend lines and in a plane substantially perpendicular to its associated bag panel when said tongue is folded through said finger openings, the top edge of said other of said

5 panels and the bend line joining said closure member to said one of said panels being in coinciding relation to each other, and the spacing between the bend line joining said closure member to said one of said panels and the bend line joining said tongue to said closure member being greater than the distance between the top edge of the other of said panels and the upper edge of the finger opening therein, to provide an outward bend in said closure member when said closure member is folded down and said tongue member is folded through said finger openings.
